UNITED STATES PATENT OFFICE.

WILLIAM SCHNELL, OF DETROIT, MICHIGAN, ASSIGNOR TO TERNSTEDT MANUFACTURING COMPANY, OF DETROIT, MICHIGAN, A CORPORATION OF MICHIGAN.

DESIGN FOR A RADIATOR CAP.

Application filed January 8, 1925. Serial No. 11,965. Term of patent 3½ years.

To all whom it may concern:

Be it known that I, WILLIAM SCHNELL, a citizen of the United States, residing in Detroit, in the county of Wayne and State of Michigan, have invented a new and original and ornamental Design for Radiator Caps, of which the following is a specification, reference being had to the accompanying drawing, forming a part thereof.

Fig. 1 is a view in perspective of the radiator cap embodying my new design.

Fig. 2 is a plan view thereof.

What I claim is:

The ornamental design for a radiator cap, as shown.

Detroit, Michigan, December 29, 1924.

WILLIAM SCHNELL.
